UNITED STATES PATENT OFFICE

HANS ANDRY NELSON, OF AJO, ARIZONA

ORE BIN STRUCTURE

Application filed November 1, 1930. Serial No. 492,818.

This invention relates to an improved storage bin construction for containing ore and analogous materials, and it has more particular reference to improved dust-proof closing means for the entrance of slots leading to the respective bins.

More explicitly, visualized, the inventor's conception comprehends a mobile tripper movable on a track structure and provided with ore discharge chutes which communicate with the entrances of said bins, said entrances being provided with flexible hinged trap doors, and said chutes being provided with means for cooperating with the doors for opening the doors sufficiently to allow the discharge of ore from the chute into the bins, and subsequently allow the doors to drop down to closed position.

The particular structural details and their relative arrangement and association will become more readily apparent from the following description and drawings.

In the drawings:—

Figure 1 represents a fragmentary top plan view showing the general assembly and cooperation of parts, certain of the trap doors being broken away and certain trap doors on the opposite sides being twisted to open position.

Fig. 2 is a side elevation showing the details of the trap door lifting means.

Fig. 3 is a transverse sectional view through the upper part of a bin constructed in accordance with the invention with the tripper and its chutes in elevation.

Fig. 4 is an exaggerated longitudinal section through the discharge end of one of the chutes.

Attention is first invited to Fig. 3 wherein it will be observed that the storage bin is denoted by the numerals 9 and 10. The numeral 11 designates generally a supporting or central roof structure or the like of appropriate arrangement. Embodied in this structure are spaced parallel T-beams 12. These constitute supports for the rails 13 and the rails serve to accommodate the transporting means of the tripper. The tripper is generally denoted by the numeral 14 and comprises a container having a pulley 15 accommodat-

ing the endless ore delivery belt 16. This tripper is provided with a pair of downwardly diverging discharge chutes 17 which are located to empty through the spaced parallel entrance openings or slots leading to the bins 9 and 10.

In this connection, I call attention to the flat formation, the slot on each side being defined by horizontal wooden stringers 18 and 19. These stringers serve to support the trap doors 20. I provide a multiplicity of these doors, and these are of flexible belting material 21 having flexible metal reinforcing straps 22 connected thereto. One longitudinal edge portion of each door is bolted down as at 23 on the outer stringer 19 to provide a hinge mounting.

The free swingable edge portion of each of the trap doors is designed to be lifted as the tripper 14 moves back and forth on the rails 13, so as to uncover the slot and to permit the ore to be discharged into the respective bins.

To accomplish this, I provide special head structures on the discharge ends of the respective chutes 17. Each head structure 75 comprises a centralized nozzle forming portion 24 on opposite sides of which are lifting shoes 25. These shoes are in the nature of extensions formed from thin sheet metal 26 and reinforcing straps or wear strips 27. 80 The pointed end portions of these shoes are designed to ride beneath the swingable ends of the trap doors. The head structure embodies attaching brackets 28 secured to opposite sides of the adjacent or companion chutes. 85

The numerals 29 designate depending shields. The numeral 30 designates a protector guard secured by suitable attaching brackets 31 to the movable tripper. This guard acts to force the doors downwardly 90 under the driving mechanism of the tripper.

The gist of the inventive conception is founded on a suitable or appropriate ore receiving bin, which is here shown as characterized in its top portion with spaced parallel longitudinal slots defining entrance openings thru which the ore is delivered from the movable tripper into the bin.

These slots are defined by spaced parallel horizontal stringers which constitute mount- 100

ing means for a plurality of individual flexible trap doors and the primary purpose of the trap doors is to provide dust sealing or trapping means to prevent the dust from flying out of the bins as the ore is dumped there into.

The arrangement is characterized by a double-acting longitudinally movable tripper embodying the container in which the conveyor has feeding connection. The tripper is of a duplex type that is embodying discharge chutes leading down through and in communication with the intake slots of the bin. Means, including pointed lifting shoes and a nozzle is provided on the discharge end of each chute for sliding beneath and successively lifting the trap doors to permit ore to be properly discharged to allow the trap doors to drop down by gravity to normally closed position.

In operation, it is apparent that the tripper 14 is suitably supported on the rails and to move back and forth in the conventional manner. Likewise, the ore (not shown) is delivered on the conveyor belt into the intake portion of the casing or housing of the tripper and is then discharged by gravity simultaneously through the discharge chutes 17. Inasmuch as the chutes are provided with lifting shoes on the discharge ends, as the shoes rise beneath and are in sliding contact with the doors, it is evident that the doors are lifted and the ore slid into the bins in an efficient manner.

The present embodiment of the invention has been disclosed in considerable detail merely for the purpose of exemplification since in actual practice, it attains the features of advantage enumerated as desirable in the statement of the invention and the above description.

It is to be understood that by describing in detail herein any particular form, structure, or arrangement, it is not intended to limit the invention beyond the terms of the claim or the requirements of the prior art.

Having thus described my invention, what I claim as new is:—

In combination with a storage bin having an entrance slot in its top and a closure for said slot formed of sections of flexible material, each section being connected at one edge to a part of the top of the bin adjacent the wall of the slot, reinforced strips connected with each section and spaced apart and extended at right angles from the hinged edge of the section, and spaced from said edge a movable tripper including a hopper having a discharge spout for extending into the slot and a pointed member on each end of the spout, said pointed members and the spout having downwardly and outwardly sloping side walls against which portions of the closure member will rest as said portions of the closure member are lifted by the spout struc-

ture as the tripper travels along whereby the escape of dust through the slot is prevented, and a guard member connected with the tripper and having a downwardly and outwardly extending portion located above one of the pointed ends of the spout with its outer part substantially flat and located beyond the extremity of the pointed end of the spout, said guard member acting to insure the closing movement of the section of the closure member.

In testimony whereof I affix my signature.

HANS ANDRY NELSON.
